UNITED STATES PATENT OFFICE.

DANIEL D. MCCLURE, OF PORTLAND, OREGON.

DESIGN FOR AN ABDOMINAL BANDAGE.

SPECIFICATION forming part of Design No. 31,293, dated July 25, 1899.

Application filed June 27, 1899. Serial No. 722,077. Term of patent 14 years.

To all whom it may concern:

Be it known that I, DANIEL D. MCCLURE, a citizen of the United States, residing at Portland, in the county of Multnomah and State of Oregon, have invented and produced a new and Improved Abdominal Bandage, of which the following is a specification, reference being had to the accompanying drawings, forming a part thereof, in which—

10 Figure 1 is a perspective view of the bandage embodying the features of my design and viewed from the front, and Fig. 2 is a rear elevation of the bandage.

In general the design consists of a shield-15 front A, bearing a central outer panel B, its corners appearing separated from the said shield-front, and horizontally-curved and downwardly and outwardly inclined side pieces C, that extend also to the rear. The 20 bottom portions of the side pieces C terminate in longitudinally-tapering bands D, which bands extend forwardly and upwardly to the lower corners of the panel B. Tapering bands E constitute the upper rear terminals of the 25 side pieces, and these upper bands cross one

another at the back, and one band passes through the other at one side of the rear central portion of said bandage. The terminal portions of the said upper bands E extend across the front of the shield A to the upper 30 corners of the panel B. The rear or inner edges of the side pieces C and their lower bands D are curved in opposite directions, imparting a horseshoe shape to the space between these parts at the rear of the bandage. 35

The leading features of the design consist in the shield A, the panel B, free from the shield at its corners, the horizontal and vertically-arched side pieces C, and the tapering bands D and E at the lower and upper portions of the side pieces, which bands terminate at the shield. 40

I claim—

The design for an abdominal bandage herein shown and described.

DANIEL D. MCCLURE.
